LIQUID FUEL BURNING TOBACCO CURING
FURNACE

William L. Johnson, Lumberton, N. C.

Application June 13, 1946, Serial No. 676,444

1 Claim. (Cl. 126—93)

1

This invention relates to furnaces, and more particularly to a fuel burner for simply, economically, and efficiently heating a tobacco barn, in which tobacco is collected and cured prior to its use in the manufacture of tobacco products.

Tobacco barns have been heated in various ways, including with furnaces to which fuel is supplied manually. Numerous attempts also have been made to heat barns with furnaces employing fluid fuel. However, efforts to provide the desired heating have not been entirely satisfactory, due to cost, labor, inefficiency of operation, or complicated nature of structure and operation.

It is an object of the invention to provide a relatively simple, inexpensive, structure, capable of being easily installed and operated, and designed for maximum efficiency, with wearing parts which may be easily renewed, and constructed to require minimum care in its use.

Further objects and advantages of the invention will be apparent from the following description, taken in conjunction with the accompanying drawings, wherein:

Fig. 1 is a front elevation, illustrating one application of the invention;

Fig. 2, an end elevation substantially at right angles to that of Fig. 1;

Fig. 3, a vertical section on line 3—3 of Fig. 2;

Fig. 4, a section on the line 4—4 of Fig. 3; and,

Fig. 5, a detailed perspective of a baffle or partition member.

Briefly stated, the invention comprises an upright housing or casing of two horizontal sections. The lower section of the casing supports a fire-pot in the form of an annular channel member for containing fuel oil. The oil is supplied to the fire-pot by valve controlled pipe line. This fire-pot has a relatively short annular inner wall and a taller outer wall having an outwardly flaring portion extended to provide a series of stepped portions having spaced apertures for the admission of air in an inward and an upward direction for combining with the fuel in the process of combustion. An inner central down draft pipe is employed for the admission of air downwardly against a baffle plate to the fire-pot.

With continued reference to the drawings and more particularly to Figs. 1 and 2 the invention comprises a lower annular casing or housing 10 which supports the upper cylindrical casing or housing 11 in which the combustion chamber 12 is located and through which the heated gases pass into pipe 13. There is a down draft or air supply pipe 14 extending from the exterior through said combustion chamber. The down draft pipe is adjustably fastened to the upper

2

casing 11 by set screws 15. The lower casing 10 is equipped with a door 16 for easy access to the hollow channel receptacle or fire-pot 17 in which the oil is ignited as well as to the other interior parts of the burner.

Openings 18 are arranged in the lower casing 10 to allow the air to flow through the channel ring 17 into the combustion chamber 12. The oil is supplied to the burner through pipe line 19 controlled by means of valve 20. The end wall 21 of the upper casing 11 is equipped with a door 22 pivotally connected therewith by bolt 23 to allow access into the combustion chamber 12.

With reference to Fig. 3, the circular channel or trough shaped receptacle or fire-pot 17 in which the oil or liquid fuel is burned, may be supported in any desired manner. However, as illustrated, three brackets or lugs 24 which form a part of the lower casing 10 are disclosed.

The construction by means of which the necessary air is supplied to the combustion chamber is an important part of the present invention. Means is provided for supplying the air for co-mingling with the fuel upwardly from the base 20 through large openings 18 in the said lower casing and then through the small apertures 25 and 26 in the channel ring or fire-pot 17 and downwardly through the down draft pipe 14 against the partition member or baffle-plate 27 and then through the small apertures 28 in the channel ring or fire-pot 17 into the combustion chamber. The channel shaped fuel receptacle or fire-pot 17 is mounted concentrically within the lower casing near the bottom of the same and is adapted so that part of the air which is admitted from the

25 down draft pipe and part of the air which is admitted through the lower casing is directed 30 outwardly through the center of the channel ring or fire-pot 17 into the combustion chamber 12 for co-mingling with the fuel during the combustion thereof. A baffle plate 27 is supported on the inner wall of the annular channel ring or fire-pot 17. The baffle plate in turn supports an upright down draft pipe or tubular member 14. The air passes downwardly through the down

45 draft pipe 14 until it strikes baffle plate 27, then it proceeds laterally from the lower end of the said pipe to the combustion chamber 12 adjacent the surface of the fuel in the fire-pot 17.

The annular channel member or fire-pot 17 50 has its outer wall flaring upwardly and outwardly to provide a series of stepped portions. The stepped portions are likewise provided with a series of apertures 25, and 26 through which air may flow upwardly and inwardly in a manner 55 such that combustion may occur adjacent to the

top of the circular channel member 17. This manner of supplying the air both laterally and vertically has proved most effective in the economical utilization of the fuel.

The lower section of the casing 10 is provided with a door 16 supported by a pair of arms 29 which extend behind the wall of the lower section so that the door 16 will remain in place by the effect of gravity and may be easily detached. A handle 30 is provided centrally of the upper portion of the door for easy removal of the entire door. The door is preferably enlarged from bottom to top as shown so that the fire-pot 17 may be inserted or removed therethrough. The casing surrounding the combustion chamber may be formed of appropriate sections including a lower casing section 10 provided with a base ring 31 and an upper casing section 11 provided with an upper base ring 32. The base ring for the upper section is adapted to rest upon the upper edge of the lower casing section or formed integrally with either of the sections if desired.

The upper casing section 11 also may be of any desired configuration. However, for simplicity it may be formed of a combination of vertical or horizontal cylinders or casing members as shown particularly in Figs. 1 and 2. The cylinders are joined together as illustrated. A pipe 13 to carry away the heated gas and other products of combustion may be inserted over one end of the horizontal cylinder. Such pipe is extended through a tobacco barn or other structure desired to be heated.

The admission of air into the upper end of the down draft pipe 14 may be controlled by an appropriate type of butterfly valve or in any desired manner.

Fig. 5 is an enlarged perspective view of the baffle partition member 21 showing the details of its construction, the said partition member being constructed of a flat circular plate supported by four braces 33. These braces extend above and below the said plate in such a manner to allow the passage of air inwardly into the fire-pot 17 when it comes in contact with the said baffle plate partition either from above through the down draft pipe 14 or from below through the openings 18 in the lower casing section 10, and through the central vertical passage formed by the inner wall of the trough of the fire pot.

In operation oil is admitted into the annular channel or fire-pot 17 by means of a supply pipe 19 and is ignited. Air to support the combustion will pass downwardly through the down draft pipe 14 and be discharged laterally into the fire-pot. Additional air will pass through the aperture 18 into the lower casing 10. Some of this air will pass into the center of the annular channel member 17 and be discharged outwardly through apertures 28 into the fire-pot or combustion chamber while additional air will pass upwardly and through the horizontal apertures 26 and vertical apertures 25 into the combustion chamber 12.

Should oil in the channel member or fire-pot 17 overflow no harm will be accomplished. The ignition of this oil will merely serve to increase the heat within the lower section of the casing and assist in evaporation. As a safety precaution, there is provided an overflow pan 34 for catching and holding such overflow oil until it has been ignited.

The hand valve 20 in the supply line may be adjusted to control the proper supply of oil and in

like manner butterfly valve in the top of the down draft pipe 14 may be set to control the flow of air therethrough.

It will be obvious to those skilled in the art that various changes may be made in the invention without departing from the spirit and scope thereof and therefore the invention is not limited by that which is shown in the drawings and described in the specification but only as indicated in the appended claim.

What is claimed is:

An oil burning furnace comprising an upstanding housing, a plurality of spaced supporting lugs mounted on the inner periphery of said housing, a horizontally disposed fire pot positioned in said housing, said fire pot including an oil receiving trough having inner and outer walls forming a continuous trough, said inner wall being formed to provide a central vertical passage open at its upper and lower ends, an upwardly and outwardly flaring portion extending from the outer wall of said trough toward and terminating short of the inner periphery of said housing and resting on said lugs, a horizontally disposed partition member having vertically extending braces at the outer periphery of and extending above and below said partition, said partition member being mounted with the lower portions of said braces engaging on the upper edge of the inner wall of the said trough whereby said partition member is spaced above the upper edge of the said inner wall, a vertically elongated downwardly extending air supply pipe having its lower end mounted on the upwardly extending portions of said braces whereby said air supply pipe is spaced above said partition, said housing being formed adjacent its bottom with openings through the periphery thereof for supplying air below said fire pot, said upwardly and outwardly flaring portion of said fire pot being provided with apertures extending therethrough for the admission of air to said fire pot, the outer wall of said trough being provided with apertures for the admission of air, whereby some of the air passing through said openings in said housing passes through said central vertical passage of said trough and whereby other of said air passes through the apertures in said trough and flaring portion of said fire pot and air passing downwardly through said air supply pipe passes between the lower end of said air supply pipe and said partition into the fire pot.
